UNITED STATES PATENT OFFICE.

MATHIAS R. KONDOLF, OF CYNWYD, PENNSYLVANIA, ASSIGNOR TO BOXBOARD PRODUCTS COMPANY, OF PHILADELPHIA, PENNSYLVANIA, A CORPORATION OF DELAWARE.

CONTAINER AND CLOSURE THEREFOR.

Application filed October 17, 1924. Serial No. 744,194.

My improvements are primarily designed to effect the secure attachment of a closure to a container to prevent pilferage and form a tight joint between the parts.

5 In the preferred embodiment of my invention, an opening in the larger end of a tapered receptacle is closed by a lid having flaps thereon pressed against the inclined walls of the receptacle or container by a constricting band or hoop, which is preferably laced through the flanges and may be caught in notches in the container walls.

The divergence of the container walls in the direction of the cover prevents movement 15 of the fastening band in one direction and the engagement of the cover with the container walls prevents movement of the band laced through the flaps of such cover in the opposite directions, so that the lid and flaps 20 are held in close contact with the container walls. Gussets may be provided on the cover flaps and held in position by the constricting band to reenforce the corners of the containers and sheathe the notches therein.

25 The joint so formed is substantially air tight so that the containers are suitable for the transportation of powders and other fluids. Moreover the fastening means may be secured with either the cover or the container in the superincumbent position. This adaptability renders my improvements particularly useful in packing fruit, vegetables, or pomiform articles so as to provide an attractive display layer of larger area than the 30 remainder of the pack and with the apices of its constituents in a regular plane. In such usage, the closure is used as a base or support for the initially deposited display layer in the formation of a tapered pack, the 35 container is telescoped over the completed pack and the constricting band is drawn up and fastened; the closure retaining the pack in the container while the package is turned to bring the closure and display layer up- 40 permost.

The characteristic features and advantages of my improvements will more fully appear from the following description and the accompanying drawings of illustrative 45 embodiments of my invention.

In the drawings, Fig. 1 is a perspective view of a flattened out closure comprised in my invention; Fig. 2 is a perspective view

showing the application thereof to an inverted tapered container; Fig. 3 is a broken 55 perspective view of a container with the closure uppermost; Fig. 4 is a sectional view taken on the line 4—4 of Fig. 3; Fig. 5 is a perspective view of spaced blanks from which the container is formed and showing 60 how the corner sections are rendered yielding to the band; Fig. 6 is a broken perspective view of a container with a modified form of closure and fastening band applied thereto; Fig. 7 is a plan view of the perforated intermediate blank shown in Fig. 5, and Fig. 8 is a plan view of the modified 65 form of cover and fastening band shown in Fig. 6.

The improved closure and fastening means 70 comprised in my invention are preferably used in conjunction with a tapered receptacle or container having its mouth at its larger end and formed by gluing together under pressure a plurality of blanks A, B 75 and C (shown in Fig. 5 in process of being telescoped within one another). The intermediate blank or core B (shown in plan in Fig. 7) has apertures b formed in zones of the end walls B' and side walls B'' which 80 when overlapped as shown in Fig. 5 form the corners of the intermediate layer of the completed container. In the completed container, the registering holes b at each corner of the core B are covered by the walls of 85 the external blank A and the internal blank C, but provide soft or yielding spots where the container wall may be readily notched.

The closure for the container comprises a median section 1 closing the mouth of the 90 container and a peripheral rim or apron overlapping the container walls, and preferably consisting of flaps 3 hinged to the section 1 along the score lines 2. The flaps 95 contain apertures 4 through which is laced or threaded a tension member or peripheral band 5.

As illustrated in Figs. 1 to 4 inclusive, the band 5 may be constricted to tightly press the flaps 3 against the container walls A by 100 means of a tightener and catch journaled in a bushing 6 set in one of the flaps 3. The tightener preferably comprises a bar bent to form a spindle loop 7 passing through the bushing 6 and arms 8 extending parallel 105 to the outer surface of the flap and terminat-

ing in the latching fingers 10. A sheave 9 is sleeved on the spindle 7 and held thereon between the flap 3 and container wall A by the ends of the band 5 which pass through axial holes 11 in the sheave and through the spindle 7. Sockets 13 are formed in the flap 3 around the axis of the tightener and in the path of the detents 10, which automatically engage therein to prevent slackening of a 10 taut band.

A tapered pack of fruit or other objects may be formed upon the section 1 within a flexible endless retainer D seated thereon, and a container telescoped over the pack and 15 retainer, as indicated in Fig. 2. By rotating the tightener arms 8 the ends of the band 5 are wound on the sheave 9 to constrict the band and draw the container and closure tightly together. The engagement of the 20 fingers 10 in the sockets 13 prevents the slackening of the band 5, which may be secured in taut condition by sealing the detents in their sockets.

The bite of the tightened wire 5 against 25 the parts of the blank A adjacent to the apertures b depresses such parts and forms notches or indentations b' at the corners of the container for confining the band.

As illustrated in Figs. 6 and 8, the side 30 flaps 3 are provided with gussets or tabs 3' for covering the notches b' and reenforcing the tops of the corners of the package, the free ends of the gussets being overlaid by the end flaps 3. The gussets, as well as the flaps, 35 are drawn tightly against the container by the flat band 5 threaded therethrough and held taut by crimping together its ends within the clip 14. The gussets 3' are, of course, equally applicable to the structure 40 shown in Figs. 1 to 4.

The interlocking of the fastening band 5 in the notches b' is effected without rupturing either the outer or inner surface of the container, and the reenforcement afforded 45 by the gussets 3' obviates any possibility of crushing the box corners or disengaging the band 5 from the notches.

Having described my invention, I claim:

1. The combination with a tapered container having an opening at its larger end, 50 of a closure having a rim including a band surrounding said container between the larger and smaller ends thereof and forming, when fastened, an inexpandible constricting device of smaller perimeter than the perimeter of said container opening and non-detachably secured to said rim, securing said rim to said container.

2. The combination with a tapered container, 55 of a closure therefor having flaps movable independently of one another, and a band substantially parallel with the free edge of said flap for securing said flap against said container without passing therethrough, said closure being detachable from

said container without removing said band from said closure.

3. The combination with a container having a wall containing a weakened spot relatively more yielding than the adjacent wall 70 section, of a closure having a band connected therewith and engaging said yielding spot.

4. The combination with a container having indented imperforate corners, of a removable closure lapping the external surfaces of said container between said indented corners having connected therewith a band seated in said indentations. 75

5. The combination with a container, of a closure having flaps engaging the walls of said container and provided with hinged gussets overlapping and reenforcing the corners thereof, and a band threaded through said flaps for securing said closure and container together. 80

6. The combination with a laminated container comprising a layer containing an aperture covered by another layer, of a closure having connected therewith a band engaging said container adjacent to said aperture and depressing a section of said last named layer into said aperture. 90

7. A container comprising a folded blank having apertures at the corners thereof, and blanks within and without said first named blank and covering the apertures therein, said blanks being permanently secured together and forming an integral body having an open side. 95

8. A container closure comprising a cover with flaps hinged thereto, a tension member threaded through said flaps, a spool connected with said tension member, a handle for rotating said spool, and a catch for holding said spool against rotation. 105

9. The combination with a tapered container of a closure therefor, and means for securing together said container and closure and comprising a tension member, a revolute means for tightening said tension member, and a catch for securing said means. 110

10. The combination with a tapered container, of a closure overlapping the tapered surface of the container, a tension member threaded in said closure and engaging the tapered surface of the container, a spool journaled relatively to the closure and connected with said tension member, and a catch for said spool. 115

11. A container closure having a flap, a journaled spool, a catch for said spool, and a tension member connected with said spool and having a threaded connection with and engaging said flap. 120

12. A container closure having a flap, a journaled spool, an arm connected with said spool and having a catch thereon for engaging apertures in said closure, and a tension member tightened by said spool and 130

having a threaded connection with an engaging said flap.

13. A container closure having a flap with a spool journalled thereon, said flap containing recesses around the axis of said spool, an arm connected with said spool and having thereon a detent for engagement in said recesses, and a tension member tightened by the rotation of said spool and engaging said closure.

14. The combination with a container and a closure therefor, of means for securing said container and closure together and comprising a spool housed between said container and closure, and a tension member operable by said spool and engaging said container and closure.

15. The combination with a tapered container having therein a tapered endless flexible pack retainer, of a closure having edge flaps and a tension member laced through said flaps and holding them against said container, said tension member being re-

movable from said container without disengagement from said closure.

16. The combination with a tapered container of rectangular cross section having an opening at its larger end, of a closure covering said opening and having flanges independently movable and lapping the external tapered sides of said container, a constricting band having a threaded connection with said flanges, means for fastening the ends of said band in constricted position, said band when constricted having a smaller perimeter than the edge of said opening and when fastened being disengageable from said container without unthreading from said flanges, said closure being held against disengagement from said container when said band is constricted and being removable from said container when the ends of said band are released.

In testimony whereof I have hereunto set my name this 16th day of October, 1924.

MATHIAS R. KONDOLF.
